ASH TRAY

Thomas Harold Kinkade, Williamsport, Pa.

Application May 25, 1951, Serial No. 15,311

Term of patent 3½ years

(Cl. D85—2)

To all whom it may concern:

Be it known that I, Thomas Harold Kinkade, a citizen of the United States, and a resident of Williamsport, in the county of Lycoming and Commonwealth of Pennsylvania, have invented a new, original, and ornamental Design for an Ash Tray, of which the following is a specification, reference being had to the accompanying drawings, forming part hereof.

In the drawings:

Fig. 1 is a top plan view of an ash tray, showing my new design;

Fig. 2 is a bottom plan view;

Fig. 3 is a side elevational view; and

Fig. 4 is a vertical sectional view thereof taken on line 4—4 of Fig. 1.

I claim:

The ornamental design for an ash tray, substantially as shown.

THOMAS HAROLD KINKADE.
